SKI CARRYING CASE

Harvey Eisenberg, 7 Demarest Road,
Livingston, N.J. 07039

Filed Feb. 17, 1972, Ser. No. 227,345

Term of patent 14 years

Int. Cl. D3—02

U.S. Cl. D87—1 R

FIG. 1 is a front elevational view of a ski carrying case showing my new design;

FIG. 2 is a top plan view;

FIG. 3 is a rear elevational view;

FIG. 4 is a bottom plan view;

FIG. 5 is an elevational view looking from the right of FIG. 1;

FIG. 6 is an elevational view looking from the left of FIG. 1;

FIG. 7 is a bottom plan view in open position;

FIG. 8 is a rear elevational view thereof;

FIG. 9 is a front elevational view thereof;

FIG. 10 is a top plan view thereof;

FIG. 11 is an elevational view thereof on an enlarged scale looking from the right of FIG. 7;

FIG. 12 is an elevational view thereof on an enlarged scale looking from the left of FIG. 7;

FIG. 13 is an enlarged cross-sectional view taken on the line 13—13 of FIG. 7;

FIG. 14 is an enlarged cross-sectional view taken on the line 14—14 of FIG. 7;

FIG. 15 is an enlarged cross-sectional view taken on the line 15—15 of FIG. 7; and

FIG. 16 is an enlarged cross-sectional view taken on the line 16—16 of FIG. 7.

I claim:

The ornamental design for a ski carrying case, substantially as shown:
